UNITED STATES PATENT OFFICE

FRANK J. ABEL, OF NEW YORK, N. Y., ASSIGNOR TO SUN RISE LAMP MFG. CO. INC., A CORPORATION OF NEW YORK

DESIGN FOR A HANDLE FOR SMOKERS' STANDS OR ARTICLE OF ANALOGOUS NATURE

Application filed August 30, 1930. Serial No. 36,833. Term of patent 3½ years.

To all whom it may concern:

Be it known that I, FRANK J. ABEL, a citizen of the United States of America, and a resident of the city of New York, in the county of Bronx and State of New York, have invented a new, original, and ornamental Design for a Handle for Smokers' Stands or Article of Analogous Nature, of which the following is a specification, reference being had to the accompanying drawing, forming a part hereof.

Figure 1 is an elevational view showing one side of the handle for smokers' stands or article of analogous nature, the opposite side being the same; and

I claim:

The ornamental design for a handle for a smoker's stand or article of analogous nature substantially as shown and described.

FRANK J. ABEL.
